UNITED STATES PATENT OFFICE.

WILLIAM THOMAS BUCKINGHAM ROBERTS, OF LEICESTER, ENGLAND, ASSIGNOR TO
UNITED SHOE MACHINERY CORPORATION, OF PATERSON, NEW JERSEY, A COR-
PORATION OF NEW JERSEY.

GRADING MACHINE.

Application filed September 13, 1922, Serial No. 588,000, and in Great Britain September 16, 1921.
Renewed October 11, 1926.

This invention relates to grading machines and is herein illustrated as embodied in a machine designed to split or even leather blanks.

5 In the manufacture of boots and shoes it is desirable that certain blanks such for example as sole blanks should be split or skived to a uniform thickness throughout their whole extent or throughout some 10 selected locality, the thickness of the finished blank being preferably the thickness of the thinnest spot in said locality. It is also desirable in some instances that the blanks should be marked and sorted in accordance with their thickness. The term 15 "grading" in the boot and shoe industry is used generically to cover these and similar operations such as visually indicating the thickness of a blank by means of a pointer 20 movable over a scale. Such machines ordinarily comprise feeler mechanism, grading mechanism and means for adjusting the grading mechanism in accordance with the determinations of the feeler mechanism, the 25 blanks being presented one by one to the feeler mechanism and fed from that mechanism to the grading mechanism.

Until recently such machines have been so constructed that a preceding blank must pass 30 entirely through the machine before a succeeding blank can be presented to the machine. This rendered the operation of such machines rather slow; and recently it has been proposed to provide a construction 35 whereby a succeeding blank may be presented to the machine and caused to operate the adjusting mechanism before the grading of the preceding blank has been completed, two such machines being disclosed respectively in application Serial No. 250,644, filed 40 Aug. 20, 1918, in the name of Winkley and in application Serial No. 305,106, filed June 18, 1919, in the name of Stewart, both of which applications are assigned to the assignee of the present application.

The present invention relates to improvements in the later type of machine referred to above. In the illustrative machine there is provided a setting member movement of 45 which sets or adjusts the grading mechanism, a controller for the setting member which is adjusted by the feeler mechanism into and held in a position corresponding

to the thickness of a thin spot encountered in the blank by the feeler mechanism, and a power operated actuator which at the proper time moves the setting member into a position corresponding to that of the controller. The grading mechanism thus set 55 remains set until the blank has been graded, but the controller is presently freed and returned to normal position so as to be capable of moving in response to the feeler determinations on a succeeding blank before the preceding blank has been graded.

60 Other features of the invention relate to means for ensuring that the controller shall be freed irrespective of the length of the blank which is being graded and to means for ensuring that the setting of the grading mechanism shall be maintained irrespective 65 of the thickness of the blank.

70 These and other features of the invention including certain details of construction and combinations of parts will be described as 75 embodied in an illustrative machine and pointed out in the appended claims.

Referring now to the accompanying drawings,

80 Figure 1 is a side elevation of a machine in which the present invention is embodied.

Fig. 2 is a plan of a portion of the machine showing more particularly the mechanism for adjusting the grading mechanism, and

85 Fig. 3 is a perspective showing substantially the same parts as are shown in Fig. 2.

90 Before proceeding to a detailed description of the parts of the machine, a general description of its mode of operation will be given. The blank is presented beneath a gate 5 which is normally held in raised or open position, to feeler rolls 7, 9 the upper one of which is held from bodily movement but the lower one of which may yield 95 downwardly. Separation of the rolls by the leading end of the blank releases the gate which falls until it engages the upper face of the blank. The gate rides over the upper face of the blank until the following or rear end of the blank passes from beneath the gate, whereupon the gate falls farther into closed position. During the time that the blank is passing beneath the feeler rolls and before the gate has completely fallen, the movements of the lower

or feeler roll 9 up and down in response to thinner and thicker spots adjusts certain mechanism which is connected to wedges or inclines one of which is shown at 11, so that, when the blank reaches the grading mechanism, herein shown as a splitting mechanism, at the farther end of the machine, it will be permitted to raise the gage roll 13 only far enough to cause the knife 16 to even the blank to the thickness of the thinnest spot encountered by the feeler rolls. After the gate 5 has completely fallen, the movements up and down of the feeler roll 9 are not effective to cause any further adjustment of the wedges of the splitting mechanism. After the blank has emerged from between the feeler rolls it is carried to the rolls 13, 15 of the splitting mechanism by a chain such as that shown in British Patent 18752 of 1912 to which patent further reference will be made. The blank presently encounters the rolls of the splitting mechanism, lifts the gage roll 13 to an extent determined by the position into which the wedges 11 have been adjusted and passes between the rolls, being split or evened during the passage to the thickness of its thinnest spot in that locality of the blank to which the adjusting mechanism was responsive. As will be explained this is commonly not the thinnest spot in the entire blank, but the thinnest spot in a selected locality, and usually the thinnest spot in the edge of the forepart of the blank, if the blank is a sole blank. The lifting of the gage roll 13 operates through certain mechanism to raise or open the gate once more so as to permit a succeeding blank to be fed to the machine; and this gate-opening mechanism, which is very similar to that of British Patent 18752 or 1912, referred to above, will first be described.

In the machine of the patent the construction is such that after the gate is closed it remains closed until the blank has been completely evened before it is raised to permit a succeeding blank to be presented to the feeler rolls; but, by omitting certain parts of the patented construction, the gate is caused to be opened by the raising of the gage roll 13 of the splitting mechanism as the blank raises said roll instead of by the fall of the same roll after the blank has been evened. The gate 5 is fast to the generally horizontal arm 17 of a bell-crank lever which is fast to a small shaft 19 mounted to rock in the frame of the machine. The other arm 117 of this bell-crank lever has nothing to do with the gate controlling mechanism, and its function will be described later. The arm 17 and gate 5 are held in their raised position, as shown, by a latch 21 which engages a pin 23 fixed in the arm, said latch being urged toward the pin by a spring-pressed plunger 25 mounted in a lever 27 to the outer end of

which the latch 21 is pivoted. The lever 27 is pivoted on a stud 29 and carries at the end remote from the latch a cam roll 31 held in engagement with a one-revolution cam 33 by a leaf spring 35. The cam 33 is fast to a 70 rotatable shaft 37 driven by intermediate gearing (not shown), which may be the same as in the patented machine, from a shaft 39 which is caused to make one revolution when the gage roll 13 of the splitting 75 mechanism is raised. The one-revolution clutch, which is connected to and disconnected from the shaft 39, is the same as in the patented machine and comprises a sliding, toothed clutch member 41 which is normally held in inoperative position by a swinging wedge 43 pivoted to the frame at 45 and having a horizontally extending arm 47 arranged to be engaged on its under side by a trip-rod 49. This trip-rod is pivoted at its lower end to an arm 51, the pivotal connection not being shown since both the trip-rod and the arm have been broken away so as not to obscure the showing of certain other mechanisms. The arm 51 is pivoted at 53 to the frame of the machine and has pivoted to it at 55 the lower end of a rod 57 the upper end of which is fast to the vertically 80 85 90 95 100 105 110 115 120 125 130 7, 9, the arm 65 is swung back into the position shown, the spring-pressed plunger 25 maintaining the pin 67 in contact with the arm. As soon as the blank raises the roll 13 of the splitting mechanism, the lever 27 is rocked first in a direction to lower the latch 21 until it once more engages the pin 23 on the gate-carrying arm 17 and then in a direction to raise the latch and open the gate 10 so that a succeeding blank may be presented to the machine.

The feeler mechanism, the splitting or evening mechanism and a large part of the mechanism by which the splitting mechanism 15 is set in accordance with the determinations of the feeler mechanism are or may be substantially the same as those shown and described in British Patent 17,808 of 1909, and those parts which are substantially the same 20 will be only briefly described.

The splitting or evening mechanism is like that of the patent and comprises the two rolls 13, 15, stationary knife 16 and inclines or wedges 11 which have been referred to 25 above. On the top of the bearing of the gage-roll 13 are fixed or formed two inclines one of which is shown at 69, both of which taper in the same direction and above them respectively are the two inclines 11 which 30 both taper in a direction opposite to that of the lower inclines 69. The upper inclines are fast to or integral with a horizontally 35 slideable rack-bar 71 so that, by adjusting the rack-bar into different positions, the distance to which the roll 13 may be raised above the edge of the knife 16 by the blank, as it enters between the rolls 13, 15, and hence the thickness to which the blank will 40 be split, may be controlled. The rack-bar meshes with a pinion 73 fast to the upper 45 end of a vertical shaft 75 to the lower end of which is fast a second pinion 77 meshing with teeth formed on the side of a horizontally 50 slideable rack-bar 79 so that the position to which the rack-bar 79 is adjusted determines the position of the wedges 11 and consequently the thickness of the finished work. The final position of the rack-bar 79 is determined by the angular position into 55 which a rock-shaft 81 is adjusted by the up and down movements of the feeler roll 9. Fast to the same rock-shaft 83 to which the latch-tripping arm 65, previously referred to, is fastened, is an arm 85, which is connected with the bearings of the lower roll 9 by mechanism (not shown), which is the same as that of the machine of British Patent 17808 referred to above, and swings 60 up and down as thinner or thicker spots are encountered in the blank by that roll. Formed on the outer end of the arm 85 is a segmental rack which meshes with a sector 87 loose on the rock-shaft 81. Fast to the rock-shaft and extending on both sides 65 of the loosely mounted sector is a member 89

(referred to hereinafter as a controller) having a face 91 with which a face on the sector is adapted to contact when the sector is rocked downwardly by the arm 85. Tension springs 93 connect the arm 85 with the member 89. With this construction the shaft 81, if permitted to, will be rocked when the arm 85 swings. Fast to the outer end of the rock-shaft 81 is a ratchet wheel 95 having for 180 degrees on its periphery 70 teeth 97 which point in one direction and for the other 180 degrees teeth 99 which point in another direction. Arranged to cooperate with the teeth 97 is a pawl 101; and arranged to cooperate with the teeth 99 80 is a second pawl 103. The pawl 101, when operative, locks the ratchet wheel 95, and consequently the shaft 81, from angular movement in response to thicker localities in the blank encountered by the feeler rolls; and the pawl 103 locks it against movement 85 in response to thinner spots, so that when both pawls are operative the ratchet wheel can not be turned. The pawl 101 is pivoted to the frame of the machine at 105 and is normally held in the inoperative position shown by a rod 107 which presses down upon the tail of the pawl. The pawl 103 is pivoted on a rock-shaft 109 and has a tail 90 which is pivotally connected by a link 111 with the arm 17 which carries the gate 5, a tension spring 113 tending at all times to pull the tail downwardly.

When, in the operation of the machine, a blank is fed beneath the open gate 5 to the feeler rolls and enters between them, the arm 85 and consequently the arm 65 is swung in a counter-clockwise direction to trip the latch 21 and allow the gate to fall upon the blank as has been described. At this time the pawl 103 moves toward the ratchet wheel 95 but not far enough to engage the teeth 99; and this condition continues, the gate riding upon the blank, until the rear end of the blank passes from beneath the gate. Before that occurs, however, the feeling operation has been carried out. As the blank is fed along between the feeler rolls the ratchet wheel 95 and shaft 81 are free to be 100 swung in either direction until the forward end of the blank lifts a shoe 115 which is adjustably mounted on a rod-like arm 119, the hub of which is pivoted on the rock-shaft 19. Extending out from the same hub 105 is the inner end of an arm 121 to the outer end of which the rod 107 is pivoted. Consequently, when the forward end of the blank passes under and lifts the shoe 115, the pawl 101 is released and swings into contact with the teeth 97 of the ratchet wheel 110 95 so that thereafter that wheel can not turn in response to thicker localities encountered in the blank by the feeler rolls. It can, however, turn in response to thinner spots and does so turn until the gate 5 rides off from 115 120 125 130

the rear end of the blank and falls to closed position. At this time the pawl 103 engages the teeth 99, and no further turning of the ratchet wheel 95 and shaft 81 in either direction is possible, these two members then occupying an angular position which corresponds to the thinnest spot encountered by the feeler rolls in the selected locality of the blank. The feeler mechanism, splitting mechanism and adjusting mechanism as thus far described are or may be substantially the same as in the British Patent 17808 referred to above, and no further details of their construction will be given.

15 In the patented machine, the rack-bar which corresponds to 79 is engaged by a sector which is fast to the shaft which corresponds to 81 so that the wedges or inclines which correspond to 11 are set directly by the turning of the shaft 81; and the gate is not opened until the blank has passed entirely through the splitting mechanism and the gage roll has been lifted by the blank and then fallen back into normal position.

20 In the present machine the rack-bar 79 is engaged by a setting member for the splitting mechanism in the form of a sector 123 which is loose on the rock-shaft 81, said setting member having a hub from which extends a locking sector 125. Extending from that side of the sector 125 which is adjacent to the controller 89, is a lug 127 having a flat upper face; and extending from the side of the controller 89 is a similar lug 129. If, therefore, after the controller 89 has been adjusted to an angular position corresponding to the thinnest spot in a blank and locked in that position, the lug 127 is moved angularly until its flat face is in alinement or register with the flat face of the lug 129, the setting member 123 will be swung into an angular position corresponding to that of the controller 89, and the rack-bar 79 will be pulled to the right a distance sufficient to set the inclines 11 in a position in which the blank will be split or evened to the thickness of said thinnest spot.

25 The mechanism for bringing the lugs 127, 129 into alinement for the purpose described comprises an actuator in the form of a striker 131 which is rockably mounted upon the shaft 81 between the hub of the setting member 123 and that of the controller 89.

30 This actuator has a flat striking face which is wide enough to engage both lugs 127 and 129, and a tail to which is pivoted at 133 the headed upper end of a connecting-rod 135.

35 The lower end of the connecting-rod is slideable through a bearing 137 and has threaded on its extreme lower end a nut 139. A coiled spring 140 surrounds the rod between the head of the rod and the bearing 137. The bearing is pivoted on a crank-pin 141 which is carried by a disk 143. The disk is loose

on a constantly rotating shaft 145 but may be connected thereto by a one-revolution clutch controlled by an arm 147. The arm is actuated to throw in the clutch by a rod 149 pivoted at 151 to the lower end of the vertical arm 117 of the bell-crank lever, the horizontal arm of which is indicated at 17. The rod 149 is held up against a pin 153 on the arm 147 by a tension spring 155 and has formed on it a shoulder 157 arranged to engage the pin when the rod is pushed to the left. This movement of the rod throws in the clutch. In order to throw out the clutch so as to bring the crank-pin 141 to rest after a single revolution a bend 159 in the rod is engaged by the crank-pin. The clutch itself has not been shown since its details form no part of the present invention, and any suitable one-revolution clutch may be employed. It will be understood, however, that when the rod 149 is moved to the left the disk 143 and crank-pin 141 make one revolution and come to rest.

40 The rod 149 is moved to the left when the rear end of the blank passes from beneath the gate 5 and permits the gate to fall. At this time, it will be recalled, the ratchet wheel 95, shaft 81 and controller 89 have been moved angularly into a position corresponding to the thinnest spot in the blank 95 and locked in that position by the pawls 101, 103. Consequently, when the crank disk 143 is caused to make one revolution it first rocks the actuator 131 yieldingly in a direction to bring the flat faces of the lugs 127, 129 into alinement or register and then in a direction to return it to its normal position. The extent to which the actuator may be rocked in a clockwise direction depends upon the position of the lug 129; and, since this position varies with different blanks, some sort of yielding connection such as the spring 140 is desirable. The actuator thus operates to swing the setting member 123 into a position corresponding to the thickness of the thinnest spot in a blank. In order to maintain the setting member, and with it the inclines 11, in this position a pawl 161 is arranged to engage the locking sector 125. This pawl is pivoted on the rock-shaft 109 and has a tail to which is pivoted at 163 the lower end of a link 165, the upper end of which is pivoted to an arm 167 which is fast to the rock-shaft 19 so that, when the gate 5 falls behind the blank 120 and the shaft 19 is rocked, the pawl 161 moves into operative relation to the locking sector 125 and holds the setting member 123, and through it the rack-bar 79 and inclines, in the position to which it was swung by the actuator 131.

45 The pawls 103 and 161 remain in operative position until the forward end of the blank lifts the gage roll 13 of the splitting mechanism and the gate 5 is raised once 130

more. With regard to the pawl 101, which should also be released at this time, if the rear end of the blank has passed from beneath the member 115, this pawl will be released. If, however, the blank is so long that its rear end is still beneath the member 115 when the gate 5 is opened, the pawl will still be operative. In order to ensure the withdrawal of the pawl 101 when the gate is opened, a link 169 is pivoted at its lower end to the pawl 103 and at its upper end is slotted to receive a pin driven into the tail of the pawl 101, with the result that when the pawl 103 is withdrawn from the teeth 99, the pawl 101 is also withdrawn from the teeth 97. The slot in the link 169 is provided so that, when the gate 5 falls upon the top of the blank, the pawl 101 will not be affected.

Should the blank be so thin at its front end that when the gage roll 13 of the splitting mechanism is raised, the inclines 69 on the roll bearing are not lifted into contact with the inclines 11, the inclines 11 would be moved out of their adjusted position by the tension spring 171, which connects the rack-bar 79 with the actuator 131, as soon as the gate was raised and the pawl 161 rendered inoperative. To provide against this possibility, there is fast to the rock-shaft 109 a second pawl 173 which is also adapted to engage the locking sector 125. In order to control the operation of this pawl, there is fast to the outer end of the rock-shaft 109 an arm 175 having threaded through its free end a screw bolt 177 the head of which is held up against the under face of the arm 51 by a tension spring 179. With this construction, whenever the gage roll 13 of the splitting mechanism is lifted, the pawl 173 will engage the locking sector 125 and thus retain the setting of the inclines 11 until the blank, which is to be split, passes from between the rolls 13, 15, and the arm 51 is lowered.

The operation of the machine section by section has been described above in the course of the detailed description of the parts of the sections. Its general mode of operation will now be summarized. The rolls of the splitting mechanism and those of the feeler mechanism are rotated continuously, the remaining parts of the machine being normally at rest in the positions shown in Fig. 1 with the gate 5 in raised or open position. A blank to be evened is pushed over the usual table and beneath the gate 5 to the feeler rolls 7, 9. As the blank enters between these rolls, the lower roll 9 is depressed and causes the arm 85 to swing downwardly. The rock-shaft 83 to which its hub is fast turns in a counterclockwise direction carrying with it the arm 65 which, through the pin 67, trips the catch 21 and permits the gate to fall until it rides upon the blank. The falling of the gate into this position moves the pawl 103 toward the teeth 99 and moves the pawl 161 toward the teeth on the locking sector 125 but does not move either pawl far enough to make it operative. The partial falling of the gate also causes the trip-rod 149 to be moved to the left but not far enough to trip the clutch which controls the crank disk 143. As the blank passes along between the feeler rolls, the lower rolls 9 rises and falls as it encounters thinner or thicker spots in the blank, and the shaft 81 turns in one direction or the other in response to these movements of the roll until the leading end of the blank passes under and lifts the shoe 115. This causes the pawl 101 to be thrown in so as to prevent the shaft 81 from turning in response to any thicker spots encountered by the feeler rolls. The effective feeler operation now begins and continues until the gate 5 rides off from the rear end of the blank and falls to closed position. When this occurs, the pawls 103 and 161 are moved into operative position, and the one-revolution clutch connects the crank disk 143 with the rotating shaft 145. The revolution of the disk causes the actuator 131 to engage the lug 127 and move it into alignment with the lug 129 on the controller 89. This rocks the setting member 123 in a clockwise direction, pulls the bar 79 to the right, turns the vertical shaft 75 and moves the inclines 11 into a position corresponding to the angular position of the lug 129, said angular position corresponding, as has been explained, to the thickness of the thinnest spot in the blank. The pawl 161 by engagement with the locking sector 125 holds the inclines in adjusted position after the actuator 131 has completed its rocking movement and come to rest. The blank is now carried toward the rolls 13, 15 of the splitting or evening mechanism and presently enters between them. In doing this, it lifts the gage roll 13 and through the arm 51 and trip-rod 49 imparts one revolution to the cam 33, thereby causing the catch 21 to engage the pin 23 and lift the arm 17 and with it the gate 5. Lifting of the arm 17 swings the arm 117 to the right, said arm carrying with it the rod 149. In connection with this raising or opening of the gate it should be explained that when the rear end of the blank passes from between the feeler rolls 7, 9, the roll 9 rises under the influence of springs (not shown) and swings the arm 85 upwardly and the arm 65 to the right so that, when the catch 21 is lowered, it will be permitted to engage the pin 23. The raising of the gate 5, through the links 111, 165, withdraws the pawls 103, 161 from operative position, and through the link 169, also withdraws the pawl 101 if it has not already been withdrawn, so that a suc-

ceeding blank may be presented at once to the feeler rolls. When the gage roll 13 was lifted and the arm 51 swung upwardly, the spring 179 pulled the arm 175 upwardly and rocked the shaft 109 in a direction to cause the pawl 173 to engage the sector 125; and this pawl continues to hold the sector 125 until the blank passes from between the rolls 13, 15, and the arm 51 swings down again into the position shown.

With this construction it should be particularly noted that a succeeding blank may be fed to the machine and caused to operate the adjusting mechanism as soon as the gage roll 13 is lifted by the preceding blank and that the operation of the adjusting mechanism continues during the time that the preceding blank is being evened.

The machines of the patents referred to above are fitted with marking mechanism in addition to splitting mechanism, but since this marking mechanism is merely another form of grading mechanism it has been omitted from the present showing in order not to complicate the drawings. The term grading mechanism, as used throughout the claims, is intended to refer to any mechanism which acts upon or with reference to a blank so as to perpetuate or to facilitate the perpetuation of the determined extent of a dimension of a blank and is not limited to the particular grading mechanism which has been illustrated.

Having thus described my invention, what I claim as new and desire to secure by Letters Patent of the United States, is:—

1. A machine of the class described having, in combination, feeler mechanism, grading mechanism, and means for adjusting the grading mechanism in accordance with the thickness of a thin spot encountered in a blank by the feeler mechanism, said adjusting mechanism including a rock-shaft, a controller angularly movable in response to the determinations of the feeler mechanism, an angularly movable setting member for the grading mechanism, an actuator located between the controller and the setting member, and means set into operation at the end of the feeling operation for causing the actuator to move the setting member into an angular position dependent upon that into which the controller was moved by the feeler mechanism.

2. A machine of the class described having, in combination, feeler mechanism, grading mechanism, and mechanism for adjusting the grading mechanism in accordance with the determinations of the feeler mechanism, said adjusting mechanism including a controller having a projection thereon, a setting member for the grading mechanism also having a projection thereon, means for adjusting the controller independently of the setting member into a position dependent

upon the thickness of a thin spot encountered in a blank by the feeler mechanism and for locking the controller from movement so that its projection may act as a stop, an actuator adapted to engage both projections, and means for operating the actuator to engage the projection on the setting member and move it as far as the projection on the controller will permit.

3. A machine of the class described having, in combination, feeler mechanism, grading mechanism including a sliding member, the construction being such that the position of the sliding member governs the operation of the grading mechanism, and mechanism for adjusting the sliding member into a position corresponding to a thin spot encountered in the blank by the feeler mechanism, said adjusting mechanism including a rack-bar connected with the sliding member, a toothed member meshing with the rack and adapted when moved to move the rack-bar, said member being provided with a projection, a controller movable independently of the toothed member and also provided with a projection, means for moving the controller into a position determined by the thickness of a thin spot in the blank, an actuator and means for thereafter causing the actuator to engage the projection on the toothed member and move it into a position determined by the position of the projection on the controller.

4. A machine of the class described having, in combination, feeler mechanism, grading mechanism and means for adjusting the grading mechanism in accordance with the determinations of the feeler mechanism, said adjusting mechanism including a rock-shaft, a controller fast thereto, means for moving said rock-shaft and controller into an angular position corresponding to the determinations of the feeler mechanism, an angularly movable member loose on the shaft and connected with the grading mechanism in such manner that angular movement of the member sets the grading mechanism, and means operating thereafter for moving said member into an angular position corresponding to that of the controller.

5. A machine of the class described having, in combination, feeler mechanism, grading mechanism, and means for adjusting the grading mechanism in accordance with the determinations of the feeler mechanism, said adjusting mechanism including a rock-shaft, a controller fast thereto, means for moving said rock-shaft and controller into an angular position corresponding to the thickness of a thin spot encountered in the blank by the feeler mechanism, an angularly movable member loose on the shaft and connected with the grading mechanism in such manner that angular movement of the member sets the grading mechanism, and

means operating thereafter for moving said member into an angular position corresponding to that of the controller.

6. A machine of the class described having, in combination, feeler mechanism, grading mechanism, and means for adjusting the grading mechanism in accordance with the determinations of the feeler mechanism, said adjusting mechanism including a controller 10 movable in different directions, two locking members adapted when operative one to prevent movement of the controller in one direction and the other to prevent movement in the other direction, and means for causing one of the locking members to be rendered inoperative when the other is rendered inoperative.

7. A machine of the class described having, in combination, feeler mechanism, grading mechanism, and means for adjusting the grading mechanism in accordance with the determinations of the feeler mechanism, said adjusting mechanism including a controller movable in different directions, two 25 locking members adapted when operative one to prevent movement of the controller in one direction and the other to prevent movement in the other direction, and connections between the locking members such 30 that moving one of the members from operative to inoperative position moves the other member in a similar manner and moving the other member to either position has no effect upon the first-named member.

8. A machine of the class described having, in combination, feeler mechanism, grading mechanism, means for adjusting the grading mechanism in accordance with the determinations of the feeler mechanism, said 40 adjusting mechanism including an angularly adjustable controller, two locking members adapted, when operative one to prevent angular movement of the controller in one direction and the other to prevent movement 45 in the opposite direction, and means for causing one locking member to be rendered inoperative when the other is rendered inoperative.

9. A machine of the class described having, in combination, feeler mechanism, grading mechanism, and mechanism for adjusting the grading mechanism in accordance with the determinations of the feeler mechanism, said adjusting mechanism including 50 an angularly adjustable controller, two pawls adapted, when operative one to prevent angular movement of the controller in one direction and the other to prevent movement in the opposite direction, and connections 55 between the pawls for moving one pawl from the other when the last-named pawl is moved to inoperative position.

10. A machine of the class described having, in combination, feeler mechanism, grading mechanism, and means for adjusting the 60

grading mechanism in accordance with the thickness of the thinnest spot encountered in a blank by the feeler mechanism, said adjusting mechanism including a controller movable in one direction in response to thicker spots encountered by the feeler mechanism and in another direction in response to thinner spots, a member adapted to prevent the controller from movement in response to thicker spots, means for rendering said member operative before the feeling operation has been completed, a second member adapted to prevent movement of the controller in response to thinner spots, means for rendering said second member operative at the end of the feeling operation, means for subsequently rendering said second member inoperative and means responsive to the movement of said second member to inoperative position for rendering said first member inoperative.

11. A machine of the class described having, in combination, feeler mechanism, grading mechanism, and means for adjusting the grading mechanism in accordance with the thickness of the thinnest spot encountered in a blank by the feeler mechanism, said adjusting mechanism including a controller movable in one direction in response to thicker spots encountered by the feeler mechanism and in another direction in response to thinner spots, a pawl adapted to prevent the controller from movement in response to thicker spots, means for rendering said pawl operative before the feeling operation has been completed, a second pawl adapted to prevent movement of the controller in response to thinner spots, means for rendering said second pawl operative at the end of the feeling operation, means for subsequently rendering said second pawl inoperative and means responsive to the movement of said second pawl to inoperative position for rendering said first pawl inoperative.

12. A machine of the class described having, in combination, feeler mechanism, grading mechanism, a movable controller, a setting member for the grading mechanism movable independently of the controller, means for moving the controller into a position dependent upon the thickness of a thin spot encountered in a blank by the feeler mechanism, a gate in front of the feeler mechanism and means set into operation by the closing of the gate for moving the setting member into a position determined by that of the controller.

13. A machine of the class described having, in combination, feeler mechanism, grading mechanism, an angularly movable controller, a setting member for the grading mechanism angularly movable independently of the controller, means for moving the controller into a position dependent upon

the thickness of a thin spot encountered in a blank by the feeler mechanism, a gate in front of the feeler mechanism, and means set into operation by the closing of the gate 5 for moving the setting member into an angular position determined by that of the controller.

14. A machine of the class described, having, in combination, feeler mechanism, grading mechanism and mechanism for adjusting the grading mechanism in accordance with the thickness of a thin spot encountered in a blank by the feeler mechanism, said adjusting mechanism comprising a member normally angularly movable in response to thicker and thinner spots encountered in a blank by the feeler mechanism, a pawl for preventing movement of the member in response to thicker spots, a shoe engagement of which 15 by the blank during its passage through the machine causes the pawl to be moved to operative position, a gate in front of the feeler mechanism, means for opening the gate, and means for moving the pawl to inoperative 20 position when the gate is raised irrespective of whether the blank at that time is in engagement with the shoe.

15. A machine of the class described having, in combination, a feeler mechanism, 30 grading mechanism including a splitting knife and a pair of rolls, one of said rolls being a gage roll adapted to be lifted by a blank as it passes between the rolls, a movable controller, a setting member for the 35 grading mechanism movable independently of the controller, means for moving the controller into a position dependent upon the thickness of a thin spot encountered in a blank by the feeler mechanism, means for 40 thereafter moving the setting member into a position dependent upon that of the controller, a locking member for the setting member, and means responsive to the lifting of the gage roll by the blank for moving the 45 locking member into operative position.

16. A machine of the class described having, in combination, feeler mechanism, splitting mechanism, a setting member for the splitting mechanism, a controller, means for 50 adjusting the controller into a position dependent upon the thickness of a thin spot in the blank encountered by the feeler mechanism, and means for thereafter moving the setting member once for each blank passed 55 through the machine into a position corresponding to that of the controller.

17. A machine of the class described having, in combination, feeler mechanism, splitting mechanism, a setting member for the splitting mechanism, a controller, means for 60 adjusting the controller into a position dependent upon the thickness of a thin spot in the blank encountered by the feeler mechanism, means for thereafter moving the setting member once for each blank passed 65

through the machine into a position corresponding to that of the controller, and means for freeing the controller to permit it to be responsive to a succeeding blank before the splitting operation has been completed on a 70 preceding blank.

18. A machine of the class described, having, in combination, feeler mechanism, grading mechanism and means for adjusting the grading mechanism in response to the determinations of the feeler mechanism, said means including a rock-shaft, a controller fast thereto, means for adjusting the rock-shaft and controller into an angular position 75 dependent upon the thickness of a thin spot 80 encountered in the blank by the feeler mechanism, and means including a member loose on said shaft for setting the grading mechanism in a position corresponding to the angular position of the rock-shaft and controller. 85

19. A machine of the class described having, in combination, feeler mechanism, splitting mechanism and means for adjusting the splitting mechanism in accordance with the 90 determinations of the feeler mechanism, said means including a member movement of which into different positions sets the splitting mechanism differently, a controller, means for automatically adjusting said controller into a position corresponding to the thickness of a thin spot encountered in a blank by the feeler mechanism, and means operating after the controller has been adjusted for moving the setting member once 100 for each blank passed through the machine into a position corresponding to that of the controller.

20. A machine of the class described having, in combination, feeler mechanism, grading mechanism and mechanism for adjusting the grading mechanism in accordance with the thickness of the thinnest spot detected by the feeler mechanism in a selected portion of a blank, said adjusting mechanism comprising a setting member movement of which sets or adjusts the grading mechanism, a controller for the setting member adjustable by the feeler mechanism independently of the setting member into a position 105 determined by the thickness of said thinnest spot, a power-operated actuator, and means becoming operative after the completion of the feeling operation for moving the setting member into a position 110 corresponding to that to which the controller was adjusted by the feeler mechanism. 115

21. A machine of the class described having, in combination, feeler mechanism, splitting mechanism, and mechanism for adjusting the splitting mechanism in accordance with the thickness of the thinnest spot detected by the feeler mechanism in a selected portion of a blank, said adjusting mechanism comprising a setting member move- 120 125 130

ment of which sets or adjusts the splitting mechanism, a controller for the setting member adjustable by the feeler mechanism independently of the setting member into a 5 position determined by the thickness of said thinnest spot, a power-operated actuator, and means becoming operative after the completion of the feeling operation for moving the setting member into a position 10 corresponding to that to which the controller was adjusted by the feeler mechanism.

22. A machine of the class described having, in combination, feeler mechanism including a pair of rolls between which the 15 blank passes, splitting mechanism including a gage roll, a stop for determining the extent to which the gage roll may be lifted by a blank which passes beneath it, and means for adjusting the stop, said means including 20 a rock-shaft the axis of which is substantially parallel to those of the feeler rolls, a controller fast to said shaft, means for causing said shaft and controller to be adjusted by the feeler mechanism into a position 25 corresponding to the thickness of the thinnest spot in a selected portion of the blank, a setting member loose on the shaft, connections between the setting member and the stop, and means caused to become operative 30 after the feeling operation has been completed for moving the setting member into an angular position corresponding to that then occupied by the controller.

23. A machine of the class described having, in combination, feeler mechanism, 35 grading mechanism, a controller for the grading mechanism adapted to be adjusted in accordance with the determinations of the feeler mechanism, a member located in the path of travel of a blank from one mechanism to the other adapted, when displaced by the blank, to effect a locking action on the controller and to terminate the locking action when the blank has moved past it, and means for automatically terminating 40 said locking action if the blank exceeds a given length while said blank is still in engagement with the member.

24. A machine of the class described having, in combination, feeler mechanism, grading mechanism, a controller for the grading mechanism adapted to be adjusted in accordance with the determinations of the feeler mechanism, a member located in the path of travel of a blank from one mechanism to the other adapted, when displaced by the blank to effect a locking action on the controller, and means for terminating 55 said locking action when the blank has reached a farther position in its travel irrespective of whether the blank is still in engagement with the member.

In testimony whereof I have signed my name to this specification.

WILLIAM THOMAS BUCKINGHAM ROBERTS.
